DESIGN FOR A PHOTOGRAPHIC FILM AND
PRINT TRAY OR SIMILAR ARTICLE

Thomas G. W. Nevell, Riverside, Conn., and Frank Samet, New York, N. Y., assignors to The F R Corporation, New York, N. Y., a corporation of New York

Application February 14, 1947, Serial No. 136,902

Term of patent 14 years

(Cl. D61—1)

To all whom it may concern:

Be it known that we, Thomas G. W. Nevell, a citizen of the United States of America and a resident of Riverside, county of Fairfield, State of Connecticut, and Frank Samet, formerly a citizen of Poland, but now awaiting his final papers for citizenship in the United States of America, residing in the city, county, and State of New York, have invented a new, original, and ornamental Design for a Photographic Film and Print Tray or Similar Article, of which the following is a specification, reference being had to the accompanying drawings, forming part thereof, in which

Figure 1 is a top plan view of a photographic film and print tray, showing our new design;

Fig. 2 is a side elevational view thereof;

Fig. 3 is an end elevational view thereof; and Fig. 4 is a section on the line 4—4 of Fig. 1.
We claim:

The ornamental design for a photographic film and print tray or similar article, as shown.

THOMAS G. W. NEVELL.
FRANK SAMET.
